UNITED STATES PATENT OFFICE.

MORRIS KLOSNER, OF NEW YORK, N. Y.

RHEOSTAT.

Application filed March 3, 1922. Serial No. 540,783.

To all whom it may concern:

Be it known that I, MORRIS KLOSNER, a citizen of the United States, and resident of New York city, in the county of New York and State of New York, have invented certain new and useful Improvements in Rheostats, of which the following is a specification.

This invention relates to electric rheostats, and has for its object the provision of a device of this character which is adapted for accurate and fine adjustment of current in a circuit.

In carrying out my invention I employ a single turn resistance element in conjunction with a main resistance element of the character generally employed in rheostat construction, said elements mounted on a common base, separate contact members for engaging said elements, and means for alternately operating said contact members in unison and independently, as hereinafter fully described and specifically set forth in the appended claims.

In the accompanying drawings forming part of this specification, Figure 1 is a face view of my improved rheostat;

Fig. 2 is a sectional elevation taken on the line 2—2 of Fig. 1;

Fig. 3 is a cross section taken on the line 3—3 of Fig. 2;

Fig. 4 is a rear elevational view of the rheostat; and

Fig. 5 is a diagrammatic view illustrating the rheostat in an electrical circuit.

In the drawings, 1 indicates a circular base composed of adaptable insulating material, said base being fixed to a switch-board or other panel 2, by means of bolts 3.

Rotatively mounted through a central bore of the base 1, is a tubular shaft 4, having a reciprocative and rotative solid shaft 5 extended therethrough; said tubular shaft being held against sliding movement, in relation to the base 1, by means of screw-threaded washers, 6 and 7, which are threaded peripherally on the shaft 4, as clearly shown in Fig. 2 of the drawings. Fixed to the forward end of the shaft 5 is a knob or handle 5^a adapted for use in the manual operation of the rheostat. The end of the tubular shaft 4, adjacent to the knob 5^a, is provided with radial serrations 8, which are adapted for interlocking engagement with a pin 9 extended diametrically through and fixed to the shaft 5.

Mounted within a segmental recess of the base 1 is a resistance element 10, which is wound on an insulator-core 10^a, and is in contact with a switch-arm 11 fixed to the tubular shaft 4 by means of a nut 12 which clamps the head of said switch arm against the washer 7, whereby the switch-arm 11 is adapted to be operated by rotation of said shaft 4.

Fixed to the end of the shaft 5, farthest from the handle 5^a, is a resilient switch-arm 13 having a right-angularly extended contact member 14 provided with a V-shaped bend 15, which engages an annular V-shaped groove 16 of the base 1, and an oblique extension 17, which contacts with a single-turn resistance element 18.

Fixed to the face of the panel 2 is a disc 19 having a calibrated scale 20; and a pointer 21 is fixed to the tubular shaft 4 for registration with said scale.

Projecting from the base 1 are two stops 22, 23 for limiting the swinging movement of the switch arms 11 and 13, said stops being covered with suitable insulating material; also mounted on the base 1 are two binding-posts 24, 25.

One terminal of the resistance element 18, is electrically connected with the shaft 5, by means of a wire conductor 26 having a flexible coil-extension 27 which is fixed to a post 28, of said shaft 5, and the other terminal of the resistance element 18 is in electrical connection with the binding-post 25, by means of a conductor 29; and the binding-post 24 is connected to one terminal of the resistance element 10, by means of a conductor 30. The rheostat is adapted to be connected to an external circuit by means of conductors 31, 32.

In the operation and use of the rheostat, the knob 5^a together with the shaft 5 are moved, in the direction of the arrow a, Fig. 2 of the drawing, sufficiently to cause interlocking engagement of the pin 9 with the serrated end of the tubular shaft 4, this movement throws the contact member 17 of the contact arm 13 back out of electrical connection and contact with the resistance element 18 whereupon the two shafts may be rotated in unison and the contact member 11 may be swung on the rheostat 10 for making an approximately required, or rough adjustment, then by pulling the knob back to its initial position, as shown in Fig. 2 of the drawings, the shaft 5 may be independently

rotated for the purpose of effecting a very fine adjustment.

I do not desire to limit myself to the specific structural and mechanical details as herein shown and described, as under the spirit of my invention, I believe that I am entitled to employ such structural variations as may fall within the scope of the appended claims.

10 Having thus described my invention, what I claim as new and desire to secure by Letters Patent, is:

15 1. In a rheostat, a helically wound resistance element, a single turn resistance element and a contact member in permanent contact with the wound resistance element and a tubular shaft connecting said contact member, a contact member in detachable engagement with the single turn resistance element, a reciprocative shaft extended through said tubular shaft and secured to said last named contact member, and means for rotating said shafts either in unison or independently.

25 2. In a rheostat, a rough adjustment resistance element and a fine adjustment resistance element, a contact member for said rough adjustment resistance element, and a contact member for said fine adjustment resistance element, means including a single control knob for moving both of said contact members continuously in either direction, and means associated therewith for moving said fine adjustment contact member continuously in either direction by said control knob independently of said rough adjustment contact member.

30 3. In a rheostat, a rough adjustment resistance element and a fine adjustment resistance element, a contact member for said rough adjustment resistance element, and a contact member for said fine adjustment resistance element, means including a single control knob for simultaneously moving both of said contact members continuously in either direction, and means associated therewith for moving one of said contact members continuously in either direction independently of the other.

35 4. In a rheostat, a rough adjustment resistance element and a fine adjustment resistance element, a contact member for said rough adjustment resistance element, and a contact member for said fine adjustment resistance element, means including a single control knob for moving both of said contact members continuously in either direction, and means associated therewith for moving one of said contact members continuously in either direction either in unison with the other contact member or independently of it.

40 5. In a rheostat, a base, a rough adjustment resistance element supported thereby on one face thereof, a fine adjustment re-

sistance element supported by said base on the peripheral surface thereof, individual contact fingers for each of said elements and adapted to move over the same from end to end, and means for manually effecting the movements of said contact fingers.

5 6. In a rheostat, a substantially circular base provided with a groove in the peripheral surface thereof, a helically wound resistance element supported by one face of said base, and a single wire positioned in said groove in the peripheral surface of said base, individual contact fingers for said element and wire, and means for moving said contact fingers.

10 7. In a rheostat, a substantially circular base provided with a groove in the peripheral surface thereof, a helically wound resistance element supported by one face of said base, and a single wire positioned in said groove in the peripheral surface of said base, individual contact fingers for said element and wire, and a single control knob for moving both of said contact fingers.

15 8. In a rheostat, a substantially circular base provided with a groove in the peripheral surface thereof, a helically wound resistance element supported by one face of said base, and a single wire positioned in said groove in the peripheral surface of said base, individual contact fingers for said element and wire, a single control knob for moving both of said contact fingers, and means for moving one of said fingers either in unison with the other or independently of it by the operation of said control knob.

20 9. In a rheostat, a substantially circular base, a rough adjustment resistance element supported by said base on one face thereof, a fine adjustment resistance wire extending substantially around and positioned on the peripheral surface of said base contact fingers for said element and wire, and means for moving said contact fingers.

25 10. In a rheostat, a substantially circular base, a helically wound resistance supported by one face thereof, a fine adjustment resistance wire wound substantially around and positioned on the peripheral surface of said base, a contact finger for said resistance, and a contact arm provided with a substantially right angle extension, for contacting with said wire, and means for controlling the movements of said finger and arm.

30 11. In a rheostat, a substantially circular base, a helically wound resistance supported by one face thereof, a fine adjustment resistance wire wound substantially around the peripheral surface of said base, a contact finger for said resistance, and a contact arm provided with a substantially right angle extension for contacting with said wire, a control knob, and means for

controlling both of said finger and arm by operation of said control knob.

12. In a rheostat, a substantially circular base, a helically wound resistance supported by one face thereof, a fine adjustment resistance wire wound substantially around the peripheral surface of said base, a contact finger for said resistance, and a contact arm provided with a substantially right angle extension for contacting with said wire, a control knob, and means for controlling both of said finger and arm by operation of said control knob to move the same in unison or said arm independently.
13. In a control device for micrometric adjustments of a rheostat or the like, a base, two concentric resistance wires fixed to said base, two centrally interposed rotatable spindles borne in said base, each carrying a contact finger cooperating with one resistance wire and a common grasp secured

to one of said spindles, rotatable with it, and displaceable longitudinally of the other of said spindles, said grasp being capable in one position of transmitting rotary motion to one of said spindles, and in the other position to engage and transmit motion to the other spindle.

14. In combination a base, a groove formed in the base, a resistance element mounted in said groove, a contact finger for engaging said resistance element, an auxiliary resistance element mounted on the peripheral surface of said base portion in which said groove is formed, and a second contact finger for cooperating with said auxiliary element.

Signed at New York City, in the county of New York and State of New York, this 8th day of December A. D. 1921.

MORRIS KLOSNER.
